CLAIM

The ornamental design for a molded holster with belt attachment, substantially as shown and described.

DESCRIPTION

FIG. 1 is a front, perspective view of a molded holster with belt attachment.

FIG. 2 is a front view of a molded holster with belt attachment.

FIG. 3 is a rear view of a molded holster with belt attachment.

FIG. 4 is a first side view of a molded holster with belt attachment.

FIG. 5 is a second side view of a molded holster with belt attachment.

FIG. 6 is a top view of a molded holster with belt attachment.

FIG. 7 is a bottom view of a molded holster with belt attachment; and,

FIG. 8 is a front, perspective view of a molded holster with an alternative belt attachment.

The broken line in the drawings depicts environmental structure of the molded holster with belt attachment that forms no part of the claimed design.
